US00D345368S

United States Patent [19]

Clark et al.

[11] **Patent Number: Des. 345,368**[45] **Date of Patent: ** Mar. 22, 1994**[54] **SURGICAL TELESCOPE**

- [75] Inventors: **Bernard Clark, Arlington, Vt.; Frederick Morris, Shrewsbury, Mass.**
- [73] Assignee: **Luxtec Corporation, Worcester, Mass.**
- [**] Term: **14 Years**
- [21] Appl. No.: **923,169**
- [22] Filed: **Jul. 31, 1992**
- [52] U.S. Cl. **D16/132**
- [58] Field of Search **359/409-410, 359/480-481; D16/130-132**

*Primary Examiner—A. Hugo Word**Assistant Examiner—CathyAnne MacCormac**Attorney, Agent, or Firm—Weingarten, Schurigin, Gagnebin & Hayes*[57] **CLAIM**

The ornamental design for a surgical telescope, as shown and described.

DESCRIPTION

- FIG. 1 is a perspective view of a surgical telescope showing our new design;
 FIG. 2 is a top plan view thereof, the bottom being a mirror image of the view shown;
 FIG. 3 is a left side elevational view thereof, the right side being a mirror image of the side shown;
 FIG. 4 is a front elevational view thereof; and,
 FIG. 5 is a rear elevational view thereof.
 The broken lines in FIG. 1 are for illustrative purposes only and form no part of the claimed design.
